Cell-O Corporation, Detroit, Mich., a corpora-
tion of Michigan

Application September 10, 1937, Serial No. 163,210

11 Claims. (Cl. 121—45)

The present invention relates to improvements in hydraulic power units adapted for use in machine tools.

One of the objects of the invention is to provide a novel hydraulic power unit which is compact, self-contained and hydraulically controlled and operated.

The unit may comprise a rotary reciprocable spindle as the movable machine element. Another object is to provide a new and improved power unit having novel hydraulic operating means in which the motive fluid is locked by valve means to prevent any movement or creeping of the spindle or machine element during idle periods.

Further objects and advantages will become apparent as the description proceeds.

In the accompanying drawings,

Figure 1 is a perspective view on a reduced scale of a machine, with the hydraulic power unit embodying the features of the invention.

Fig. 2 is a side elevational view of the hydraulic power unit with the front cover removed.

Fig. 3 is a plan view of the hydraulic power unit without the drive motor.

Fig. 4 is an end elevational view of the hydraulic power unit.

Fig. 5 is a fragmentary longitudinal sectional view of the hydraulic power unit on an enlarged scale taken substantially along line 5—5 of Fig. 3.

Fig. 6 is a diagrammatic representation of the hydraulic transmission for the unit.

Fig. 7 is a view similar to Fig. 6 but showing the transmission in condition for rapid approach.

Fig. 8 is a view similar to Fig. 6 but showing the transmission in condition for slow feed.

Referring more particularly to the drawings, the hydraulic control unit embodying the features of my invention comprises a self-contained housing 1 adapted to be adjustably mounted on a machine base 2. The unit is of the quill or ram type, comprising a suitable tool spindle 3 journaled in and movable axially with a non-rotatable reciprocable quill 4. A hydraulic operating mechanism is fully contained within the unit for imparting to the spindle 3 a cycle comprising a rapid approach, two different feeds selectively available without feed interruption or as jump feeds, a selectively available dwell at the end of the forward stroke, a rapid return, and an automatic stop.

The quill 4 extends slidably through a large cylinder 5 formed integral with the casing 1, and closed at opposite ends by suitable pilot caps 6 and 7. A piston 8 is secured to the quill 4 for

reciprocation in the cylinder 5. The quill 4, which constitutes the piston rod for the piston 8, extends from the cylinder 5 through two closely lapped hardened steel bushings 9 and 10 which are secured in the pilot caps 6 and 7, and which provide a hydraulic seal. An annular wiper plate 11, secured to the pilot cap 6, encircles the outer end of the quill 4 and prevents foreign matter from getting into the cylinder 5. A guide arm 12 is keyed to the rear end of the quill 4, and projects into a slot 13 formed in the base wall of the casing 1 parallel to the quill to prevent rotation in the course of reciprocation.

Also formed in the casing 1 is a small cylinder 14 parallel to the cylinder 5 and closed at the ends by pilot caps 15 and 16. A small piston 17 is reciprocable in the cylinder 14, and has a piston rod 18 extending slidably through sealing bushings 19 and 20 in the caps 15 and 16. A wiper plate 21 is secured to the cap 15, and encircles the outer end of the rod 18. The outer ends of the quill 4 and piston rod 18 are rigidly connected for joint movement by a suitable face plate 22. The motors or actuators, comprising the cylinder 5 and piston 8 and the cylinder 14 and piston 17, constitute a hydraulic transmission for reciprocating the spindle 3.

The forward end of the spindle 3 extends through the face plate 22, and is journaled therein in a suitable double row antifriction bearing 23. The outer raceway of this bearing is confined in a recess 24 in the plate 22 by means of an annular clamp plate 25. The inner raceway is confined against a shoulder 26 on the spindle 3 by means of a lock nut 27.

The spindle 3 preferably is tubular in form, and the outer end is ground to close limits on the inside diameter and formed with a longitudinal internal key slot 28. If the unit is to be used for single tool operation, a suitable sleeve with a taper bore (not shown) is inserted into the spindle 3. If the unit is to be used for multiple tool operation, a suitable multiple tool or drill head (not shown) may be mounted on the face plate 22 with a drive shank (not shown) fitted directly into the spindle. The clamp plate 25 is formed with an annular pilot 29 projecting from the face of the plate 22 to locate drill heads of the flange type.

The rear end of the spindle 3 is journaled in a single antifriction bearing 30 confined by a plate 31 in a bearing housing 32. This housing has an axial sleeve 33 fitted to the inner end of the quill 4, and secured thereto and to the guide arm 12 by means of a dowel pin 34.

To provide a suitable rotary drive connection, a spline bushing 35 is keyed within the rear end of the spindle by a pin 36 and is locked in position by a nut 37. A drive shaft 38 extends into the inner end of the spindle 3 and is axially splined to the bushing 35.

The shaft 38 is suitably journaled in a gear housing 39 bolted to the rear end of the casing 1 and closed by a cover 40. Also journaled in the housing 39 in parallel relation to the shaft 38 are an idler shaft 41 and a power inlet shaft 42. The shaft 38 is driven from the shaft 42 through reduction gearing consisting of a gear 43 on the shaft 42, idler gears 44 and 45 on the shaft 41 and a gear 46 on the shaft 38. The gears are 15 removably splined to the shafts. Preferably, all of the shafts are splined to the same dimension, and all of the gears have the same splined hole and the same face width. As a result, the necessary drive speed range is obtained with a relatively small number of gears, using each gear interchangeably in different positions.

The power inlet shaft 42 projects through the cover 40 for connection to a suitable source of power. In the present instance, a pulley 47 is keyed to the shaft 42, and connected through a belt 48 to an electric motor 49 on a bracket 50. One edge of the bracket 50 is pivoted by a pin 51 to a cover 52 closing the top of the casing 1, and the other edge is adjustable by means of a screw 53 for properly tensioning the belt 48. Preferably, the belt 48 is enclosed by a removable guard 54.

The hydraulic operating mechanism comprises a suitable pump 55 taking motive fluid from the interior of the casing 1, the bottom of which constitutes a sump, and discharging to a pressure line 56. The pump 55 is mounted within the casing 1 on an adapter plate 57 secured to the housing 39, and is keyed directly to the inlet shaft 42 which is driven constantly at the most convenient pump speed. The sump may be supplied with fluid through an opening 58 in one side wall of the casing 1, and normally closed by a plug 59. A screen filter 60 is mounted in the opening 58. Also mounted in the side wall of the casing 1, below the filler plug 59, is a sight gage 61.

The motive fluid in the line 56 is substantially maintained at a predetermined pressure by an adjustable relief valve 62 discharging to the sump, and is adapted to be supplied to the cylinders 5 and 14 through a control valve 63. In its present form, this valve comprises a valve bore 64 having a central pressure port 65 connected to the line 56, rapid traverse ports 66 and 67 at opposite sides of the port 65 and connected respectively through lines 68 and 69 to opposite ends of the small cylinder 14, and feed ports 70 and 71 located outwardly of the ports 66 and 67 and connected respectively through lines 72 and 73 to opposite ends of the large cylinder 5. A valve plunger 74 of the spool type is reciprocable in the bore 64, and is formed with an axial bore 75 open at opposite ends to exhaust chambers 76 and 77 connected to a drain line 78 leading to the sump.

The valve 63 is operable hydraulically under the control of two pilot valves 79 and 80 and a dwell mechanism 81. Formed on opposite ends of the valve plunger 74 are two pistons 82 and 83 which are of relatively small and large diameters, and which extend slidably into two cylinders 84 and 85 at opposite ends of the valve bore 64. The cylinder 84 is always connected to the pressure line 56 and hence is always under pressure. The cylinder

5 der 85 opens to a line 86 adapted to be connected by the dwell mechanism 81 either to a pressure line 87 leading from the valve 63 in the transverse plane of the port 65, or to a drain line 88 opening to the drain chamber 76.

The dwell mechanism 81 comprises a bore 89 connected at opposite ends to the pressure line 87 and a line 90, and having suitable intermediate port connections with the lines 86 and 88. A valve piston 91 is slidable in the bore 89, and is urged in one direction by a spring 92 to close the line 88 and connect the lines 86 and 87. Movement of the piston 91 against the action of the spring 92 serves to interrupt the connection between the lines 86 and 87 and to connect the lines 86 and 88.

The line 90 has an unrestricted branch line 93 and a parallel restricted branch line 94, under the control of the pilot valve 79. The restriction in the line 94 is provided by an adjustable orifice 95. The pilot valve 79 may be of any desired construction, and is herein shown as of the rotary type, having a bore 96 with port connections at peripherally spaced points with the lines 56, 38, 93 and 94, and having a plug 97 formed with a flow passage terminating with suitably dimensioned and located ports 98 and 99 at opposite sides of a land area 100. The plug 97 has an axial operating shaft 101 extending to one side of the casing 1 and provided with a hand lever 102. In the intermediate position of the plug 97, the lines 88 and 93 are closed, and the lines 56 and 94 are connected. In the left-hand position, the ports 98 and 99 are open to the lines 88 and 93 and the line 56 is disconnected. In the right-hand position, the lines 88 and 94 are closed, and the lines 56 and 93 are connected.

To provide means for moving the valve plunger 74 against the pressure in the cylinder 84 into feed position, a feed collar 103, having a larger pressure area than the piston 82, is slidable on the piston 83 within a cylinder 104 and for engagement with a shoulder 105 on the plunger 74. The outer end of the cylinder 104 is open to a line 106 adapted for connection by the pilot valve 80 either to the drain line 88 or the pressure line 56.

Provision is also made for forcing the valve plunger 74 into neutral position against the pressure in the cylinder 85. The means for this purpose comprises a stop collar 107, with a larger pressure area than the piston 82, slidable on the piston 82 within a cylinder 108 and for engagement with a shoulder 109 on the right end portion of the plunger 74. The outer end of the cylinder 108 is open to a line 110 adapted for connection by the pilot valve 80 either to the pressure line 56 or the drain line 88.

The pilot valve 80 may be of any desired character, and in the present instance is shown as of the rotary type, having a bore 111 with suitable peripherally spaced port connections with the lines 56, 88, 106 and 110, and a valve plug 112 with a recess 113 and connected spaced recesses 114 and 115. The arrangement is such that in stop position, the lines 88 and 106 are connected by the recess 114 and the lines 56 and 110 are connected by the recess 113, and in feed position, the lines 88 and 110 are connected by the recesses 114 and 115 and the lines 56 and 106 are connected by the recess 113. The valve plug 112 has an axial operating shaft 116 extending to one side of the casing 1.

In the feed position, the control valve 63 limits the discharge of fluid from the exhaust ends

of the motive cylinders 5 and 14 to a feed drain line 117 which is closed by the valve 80 in stop position, and which is adapted to be connected through a flow passage 118 in the plug 112 selectively to one or the other of two parallel restricted lines 119 and 120 connected respectively through adjustable orifices 121 and 122 to the drain line 78. The selective feed adjustment does not effect the various connections between the lines 56, 88, 106 and 110. The orifices 121 and 122 may be of any suitable character, and are accessible for adjustment from one side of the casing 1. It will be understood that these orifices are adjusted to provide unequal restrictions where different feeds are required.

To obtain a constant rate of feed for either orifice selection, a governor valve 123 is interposed in the drain line 78. This valve comprises a bore 124 connected at opposite ends respectively to the line 117 and a line 125 from the orifices 121 and 122, and having a port connection intermediate its ends with the line 78. A plunger 126 is slidable in the bore 124, and provides a graduated flow restriction between the lines 125 and 78. A spring 127 tends to urge the plunger 126 against the pressure in the line 117 in a direction to decrease the flow resistance. Hence, the outlet pressure of the selected orifice 121 or 122 is varied in accordance with the inlet pressure to maintain a constant orifice pressure drop and therethrough a tool feed of constant rate regardless of variations in the work load.

The pilot valves 79 and 80 are automatically controlled in accordance with the movement of the spindle 3 to define a predetermined cycle. In the present instance, the valve shafts 101 and 116 are provided at the outer ends with a plurality of triggers engageable in predetermined sequence by a selected series of dogs. These dogs may be varied as to selection and spacing to obtain the desired cycle.

An illustrative cycle comprises rapid approach, fast feed, rapid jump traverse, slow feed, dwell, reverse, rapid return and stop. To obtain this cycle, there is fixed on the outer end of the valve shaft 101 a reverse trigger 128, and on the shaft 116, a first feed trigger 129, a second feed trigger 130, and a stop trigger 131. Integral with the trigger 130 is a jump feed trigger 132. In addition, positioning arms 133 and 134 are fixed on the shafts 101 and 116, and extend with their ends in overlapping relationship so that movement of the valve 80 into stop position will effect movement of the valve 79 into intermediate or neutral position. The various triggers 128 to 132 are adapted for engagement respectively by a plurality of dogs 135 to 139 which are removably and adjustably mounted on two parallel dog shafts or rods 140 and 141 rigidly connected at their forward ends to the face plate 22 for movement therewith. The other ends of the rods 140 and 141 extend slidably through a guide bracket 142 on one side of the casing 1. In the present instance, the dogs 136, 137 and 138 are carried by the rod 140 and other dogs are mounted on the rod 141. The dog 139 is pivotally mounted in a bracket 143 on the rod 141, and is normally held in exact operative position by a spring 144 so as to be operative upon movement to the left and ineffective in the reverse direction. It will be understood that the coacting triggers and dogs are mounted on the respective supports for proper alignment longitudinally of the path of movement.

The various valves 63, 79 and 80, the dwell 75

mechanism 81 with the orifice valve 95 and the orifice feed valves 121 and 122 with the governor 123 are built into a compact hydraulic control panel 145 which is suitably mounted as a unit in one side of the casing 1. A side cover 146 secured to the casing 1 may be removed to obtain access to the panel 145. The valve shafts 101 and 116 project through the casing 1, and may be operated from either end. Thus, the lever 102 may be shifted to the stub end of the shaft 101. Similarly, a hand feed knob 147 may be secured to either end of the shaft 116. The triggers, dogs and dog bars are located in a recess 148 formed in the side of the casing 1 opposite the panel 145, and normally closed by a side cover 149. Feed shafts 150 and 151 extend from the orifice feed valves 121 and 122 into the recess 148 for adjustment, and are therein provided with suitable graduated dials 152.

As described, the valve 79 is operable manually by means of the lever 102 on the unit. If desired, a remote control may also be provided. In the present instance, this control consists of a cylinder 153 removably mounted in the forward end wall of the casing 1. A piston 154 is reciprocable in the cylinder 153, and has a piston rod 155 formed with a gear rack 156 meshing with a gear 157 on the shaft 101. Suitable fluid supply and exhaust lines 158 and 159 open from opposite ends of the cylinder 153 to the exterior of the casing 1 for connection with conduits leading to a hand or solenoid actuated valve 160 for single or multiple unit control. The valve 160 also has connections with the pressure line 87 and the exhaust line 88. In neutral position, the lines are blocked; in the right-hand valve position, pressure is supplied to the line 158 to effect rapid approach; in the left-hand valve position, pressure is supplied to the line 159 to effect rapid return.

With the parts as shown in Fig. 6, fluid under pressure is supplied to the cylinders 84, 85 and 108, and hence the control valve 63 is held in neutral position. Since the line 117 also is blocked by the valve 80, the fluid is locked in all ends of the motor cylinders 5 and 14 so that no axial spindle movement can take place.

To institute rapid advance (Fig. 7), the hand lever 102 is moved into its left-hand position. This connects the line 93 to the drain line 88, and thereupon the pressure fluid in the line 87 depresses the plunger 91 to connect the cylinder 85 through the line 86 to the drain line 88. Since there is no pressure in the cylinder 104, the pressure in the cylinder 84 will force the main valve plunger 74 fully to the left. As a result, pressure fluid is supplied from the line 56 only through the line 69 to the rear end of the small cylinder 14, and the front ends of both cylinders 5 and 14 are connected through the lines 68 and 72 to the exhaust chamber 76 and thence through the bore 75 and chamber 77 to the exhaust line 78. The line 73 is open to the chamber 77, and directs a part of the exhaust fluid into the rear end of the large cylinder 5 to keep the latter filled. The spindle 3 is advanced rapidly since the available fluid is supplied only to the small cylinder. By this means a rapid approach can be practicably obtained by the use of a small pump.

At a predetermined point in the advance or forward movement, the dog 136 will engage the trigger 129 to rock the valve 80 one step in a counterclockwise direction. The same adjustment may be made at any time by means of the

hand knob 147. As a result, the cylinder 108 is connected through the line 110, valve recesses 115 and 114 and the line 88 to the exhaust chamber 76, and pressure fluid is supplied from the line 56 through the valve recess 113 and the line 106 to the cylinder 104. Also, the feed exhaust line 111 is connected to the line 119 and orifice 121. The collar 103 now forces the valve plunger 74 against the pressure in the cylinder 84 into feed position. In this position, both lines 69 and 73 are connected to the pressure line 56, and both lines 68 and 72 are cut off from the chamber 76 and connected to the restricted line 117 to effect a feed with a heavy cutting thrust. The governor 123 maintains a constant feed rate regardless of load variations.

Subsequently, the dog 139 will engage the trigger 132 to return the valve 80 into rapid advance position. If a jump feed is not desired, the dog 139 is removed.

At a still later point in the advance movement, the slow feed dog 137 will engage the trigger 130 to move the valve 80 counterclockwise through the first feed position into a second feed position, thereby connecting the line 117 to the line 120 and orifice 122 (Fig. 8), while obtaining the other feed adjustments as previously described.

Shortly before the end of the rapid advance, the reverse dog 135 will engage the trigger 128 to rock the valve 79 clockwise into initial neutral position, and then the quill 4 will move against a positive stop and stall. Adjustment of the valve 79 brings the arms 133 and 134 toward each other, but does not affect the valve 80 which is ineffective to control the return spindle movement. The valve 79 connects the lines 56 and 94, thereby supplying pressure fluid through the dwell orifice 95 and the line 90 to the bottom of the plunger 91. After a dwell period, determined by the restriction in the valve 95, the plunger 91 reaches its top position to connect the lines 86 and 87, thereby supplying pressure fluid to the cylinder 85. Thereupon, the valve plunger 74 is moved fully into the right-hand position to connect the line 68 to the pressure line 56, and the lines 69, 72 and 73 to exhaust, for rapid return.

If a dwell is not desired, the valve 95 is adjusted to remove the flow restriction, and in this event reversal will occur immediately after engagement of the trigger 128 by the dog 135. In any event, immediate reversal can be obtained when desired by manually adjusting the valve 79 through neutral into its extreme right-hand position to connect the pressure line 56 to the unrestricted line 93 instead of the line 94.

At the end of the rapid return, the dog 138 will engage the trigger 131 to return the valve 80 to initial position and the latter through the arms 133 and 134 will insure location of the valve 79 in central position, to stop the operation. More particularly, the cylinder 104 will be exhausted and the cylinder 108 will be connected to the pressure line so that the collar 107 will shift the control valve 63 to the left into neutral position.

It will be evident that I have provided a novel hydraulic power unit which is self-contained. The unit may be employed in different machine tools and may be mounted in any suitable position. Each unit may be controlled separately or a group of units may be mounted on a single machine base and operated through a single remote control. By employing a small cylinder for rapid traverse and both a small cylinder and

5 a large cylinder for feed traverse, a small pump operating at moderate pressures may be employed. The hydraulic control valves being built into one complete panel also require very little space. As a result, the construction of the unit may be made compact. During idle periods, all of the ends of the cylinders are blocked by valves so that the spindle cannot move or creep.

I claim as my invention:

1. A self-contained hydraulic power unit comprising, in combination, a casing adapted to be mounted upon a machine frame, a spindle mounted in said casing for rotation and axial reciprocation, a small piston and cylinder motor and a large piston and cylinder motor mounted in said casing for reciprocating said spindle, and a hydraulic control mechanism in said casing, said mechanism including a main control valve having a pressure inlet and having a restricted drain outlet and an unrestricted drain outlet and having a rapid approach position in which one end of said small motor is connected to said inlet and the other ends of said motors are connected to said unrestricted drain outlet, a rapid return position in which the reverse end of said small motor is connected to said inlet and the other ends of said motors are connected to said unrestricted drain outlet, an advance feed position in which the pressure ends of said motors are connected to said inlet and the exhaust ends of said motors are disconnected from said unrestricted drain outlet and connected to said restricted drain outlet, and a stop position in which said motors are disconnected from said inlet and said unrestricted drain outlet, a pilot valve for effective movement of said control valve selectively into feed position during the approach movement or into stop position during the return movement, and when said main valve is in stop position closing said restricted drain outlet, and a second pilot valve for effecting movement of said control valve selectively into approach position for rapid traverse or feed depending on the position of said first mentioned pilot valve, or into reverse position when said first mentioned pilot valve is out of stop position, and dogs movable with said spindle for controlling said pilot valves.

2. A self-contained hydraulic power unit comprising, in combination, a casing adapted to be mounted upon a machine frame, a spindle mounted in said casing for rotation and axial reciprocation, a small piston and cylinder motor and a large piston and cylinder motor mounted in said casing for reciprocating said spindle, and a hydraulic control mechanism in said casing, said mechanism including a restricted drain outlet, a main control valve having a pressure inlet and an unrestricted drain outlet and having a rapid approach position in which one end of said small motor is connected to said inlet and the other ends of said motors are connected to said unrestricted drain outlet, a rapid return position in which the reverse end of said small motor is connected to said inlet and the other ends of said motors are connected to said unrestricted drain outlet, an advance feed position in which the pressure ends of said motors are connected to said inlet and the exhaust ends of said motors are disconnected from said unrestricted drain outlet and connected to said restricted drain outlet, and a stop position in which said motors are disconnected from said inlet and said unrestricted drain outlet, a pilot valve for effecting movement of said control valve selectively into

feed position during the approach movement or into stop position during the reverse movement, and when said main valve is in stop position closing said restricted drain outlet, and a second pilot valve for effecting movement of said control valve selectively into approach position for rapid traverse or feed depending on the position of said first mentioned pilot valve, or into reverse position when said first mentioned pilot valve is out of stop position.

3. In a self-contained hydraulic power unit adapted to be housed in a casing mounted upon a machine frame with a spindle mounted in said casing for rotation and axial reciprocation, the combination of a hydraulic transmission for reciprocating said spindle, a source of pressure fluid, an unrestricted drain, a restricted drain including a throttle orifice, a control valve reversibly adjustable to connect said source selectively to opposite ends of said transmission and adjustable during spindle movement in one direction to connect the exhaust from said transmission selectively to said restricted drain or to both of said drains and movable into stop position to disconnect said transmission from said source and said unrestricted drain, and a plurality of pilot valves operable conjointly to control said control valve, one of said pilot valves being operable to block said restricted drain when said control valve is in stop position.

4. A self-contained hydraulic power unit comprising, in combination, a casing adapted to be mounted upon a machine frame, a spindle mounted in said casing for rotation and axial reciprocation, a hydraulic transmission embodying a plurality of cylinders having pistons reciprocable therein and interconnected to move in unison for reciprocating said spindle, a source of pressure fluid, a drain, and means including a control valve for connecting a selected number less than all of said cylinders to said source and drain and for also simultaneously directing at least a portion of the pressure fluid from the forward face of a non-selected one of the pistons substantially directly to the rear face thereof and independently of said drain.

5. In combination, a hydraulic transmission for reciprocating a machine tool element, a source of pressure fluid, an unrestricted drain and a plurality of restricted drains, means for individually adjusting the restriction of said restricted drains, and means including a main control valve for connecting said transmission reversibly to said source and said unrestricted drain to impart rapid advance and return movements to the machine tool element, said last mentioned means alternatively being operable to disconnect said transmission from said unrestricted drain and to connect said transmission to said source and to one of said restricted drains for a slow feed movement of the machine tool element in a forward direction, and including a pilot valve for selecting the one of the plurality of the restricted drains to which said transmission is connected to thereby control the rate of feed in accordance with the adjustment of the restriction in the selected restricted drain.

6. In combination, a hydraulic transmission embodying a plurality of cylinders having pistons reciprocable therein and interconnected to move in unison for reciprocating a machine tool element, a source of pressure fluid, an unrestricted drain and a plurality of restricted drains, means for individually adjusting the restriction

of said restricted drains, means including a main control valve for connecting a selected number less than all of said cylinders reversibly to said source and said unrestricted drain to impart

5 rapid advance and return movements to the machine tool element and for also alternatively connecting all of said cylinders reversibly to said source and one of said restricted drains for a slow feed movement of the machine tool element

10 in one direction, said last mentioned means including a single pilot valve selectively adjustable for determining in the movement in said one direction the number of cylinders to which fluid is supplied through said main valve from said 15 source and also the one of said restricted drains to which the selected cylinders are connected.

7. The combination with a hydraulic transmission for reciprocating a machine tool element at a plurality of selected speeds, and means including

20 a rotary pilot valve for controlling the speed setting of said transmission, of a pair of spaced elongated members rigid with said machine tool element and paralleling its path of movement, an oscillatable actuator for said pilot valve projecting between said members with its axis of oscillation transverse thereto, and dogs adjustably mounted on said members for engagement with said actuator in the reciprocation of said machine tool element, the ones of said dogs on opposite ones of said members actuating to oscillate said actuator in respectively opposite directions during the course of longitudinal movement of said members in one direction.

30 8. The combination with a hydraulic transmission for reciprocating a machine tool element selectively at a feed rate, at a rapid advance rate or at a rapid return rate, means including a first rotary pilot valve for reversing the direction of movement of the transmission, means including

35 a second rotary pilot valve for changing the speed of the transmission and for stopping the same, of a pair of spaced elongated bars rigid with said machine tool element and paralleling its path of movement, oscillatable actuators for

40 said pilot valves projecting between said bars with their axes of oscillation transverse thereto, and dogs adjustable longitudinally of said bars for engaging and moving said actuators in the course of reciprocation of said machine tool element to control cyclically the operation of said transmission, said dogs including at least two arranged to operate the actuator of said second pilot valve and disposed on respective ones of

45 said pair of bars, whereby to shift said second valve in opposite senses during movement of said machine tool element in one direction.

50 9. The combination with a variable speed drive mechanism for a reciprocable machine tool element, of a pair of elongated spaced members fixed to the element and movable longitudinally with it, means including an oscillatable device

55 projecting between said members and transverse to them for controlling the operation of said drive in response to oscillation of said device, and abutments adjustably mounted on respective ones of said members at points spaced along said members from each other for contacting said device and oscillating it in respectively opposite directions during movement of the element in one direction.

60 10. In a self-contained hydraulic power unit adapted to be housed in a casing supported upon a machine frame with a spindle mounted in said

65 casing for rotation and axial reciprocation, the

combination of a hydraulic transmission for reciprocating said spindle, a source of pressure fluid, an unrestricted drain, a restricted drain including a throttle orifice and connected to said transmission to receive fluid discharging therefrom in one direction of movement, a control valve reversibly adjustable to connect said source selectively to opposite ends of said transmission and adjustable during spindle movement in said one direction of movement to connect the exhaust from said transmission to said unrestricted drain for rapid traverse or to disconnect said exhaust from said unrestricted drain for feed movement and movable into stop position to disconnect said transmission from both said source and said unrestricted drain, and a plurality of pilot valves operable conjointly to control said control valve, one of said pilot valves being operable to block said unrestricted drain when said control valve is in stop position.

20

11. The combination with a variable speed drive mechanism for a reciprocable machine tool element, of a support for said element having a recess in one side, a pair of elongated spaced members fixed to said element and movable within said recess longitudinally with said element, means including an oscillatory device projecting between said members and transverse thereof for controlling the operation of said drive mechanism by reverse oscillation of said device, said device being mounted on a shaft journaled in said support and projecting to opposite sides thereof to permit actuation from either end, and abutments adjustably mounted on respective ones of said members at spaced points along said members from each other for contacting said device and oscillating it respectively in opposite directions during movement of said element in one direction.

RUSSELL E. BAUER.
